UNITED STATES PATENT OFFICE.

ANDREW ARCHER, OF NORTH ADAMS, MASSACHUSETTS, ASSIGNOR TO CROMPTON & KNOWLES LOOM WORKS, OF WORCESTER, MASSACHUSETTS, A CORPORATION OF MASSACHUSETTS.

PICKER-STICK CHECK FOR LOOMS.

Application filed May 1, 1924. Serial No. 710,457.

This invention relates to looms in which cloth is woven with a fly shuttle, and relates more particularly to the picking mechanism of this type of loom. It has been found desirable in such looms to cushion or yieldingly check the motion of the picker stick at its desired limits of travel and particularly on its return or outward movement.

It is the general object of my invention to provide an improved device for thus checking the motion of the picker stick. With this general object in view, my invention in its preferred form provides means for yieldingly returning the picker stick to outward position, in combination with means to limit the extent of such restoring action.

My invention further relates to arrangements and combinations of parts which will be hereinafter described and more particularly pointed out in the appended claims.

A preferred form of my invention is shown in the drawings in which—

Fig. 1 is a front elevation of parts of a loom embodying my improvement;

Fig. 2 is a partial front elevation showing certain of the parts in Fig. 1 in a different position;

Fig. 3 is a sectional plan view, taken along the line 3—3 in Fig. 2, and

Fig. 4 is an enlarged front elevation of a part to be described.

Referring to the drawings, I have shown certain usual parts of a loom including a loom frame or side 10, a sword 11 mounted on a rock shaft 12, and a lay 13 mounted on the sword and providing a race for a shuttle S, reciprocated by two picker sticks 14, only one of which is shown in the drawings. Each picker stick 14 is connected by a link 15 to an arm 16 on a pick shaft 17 which is intermittently moved angularly by any usual picking mechanism to advance the picker stick and throw the shuttle across the lay. The picker stick is pivoted at 18 to a bracket or support 19 fixed to the outer end of the rock shaft 12. A yielding stop 20 is also pivoted at 21 to the bracket 19 and cushions the picker stick 14 as it approaches its extreme outward position.

The parts thus described are or may be of the usual form and in themselves constitute no part of my present invention, which relates particularly to means for

yieldingly resisting inward or operative movement of the picker stick and thereafter yieldingly returning the stick to its outward position, together with means for limiting the return action.

The mechanism for accomplishing these results comprises an arm 23 pivoted at 24 on the bracket 19 and connected at its upper end by a flexible strap 25 to the loom side 10. Below its pivot, the arm 24 is connected by a strap or link 26 to a tension spring 27 fixed to an arm adjustably secured to a cross rod 29. While the details of the yielding stop 20 form no part of my invention, it may be stated that this stop comprises a pivoted arm 30 which is yieldingly movable outward against the action of a spring 31 (Fig. 4) and that the arm 30 is provided with a leather band 32 with which the stick 14 directly engages.

Having described the construction of my invention, the operation thereof is clearly apparent. The picker stick 14, having been swung inward by the picking mechanism, engages the yielding arm 23 and swings the same to the right as viewed in Fig. 1, increasing the tension of the spring 27. As soon as the picking mechanism ceases to act and the picker stick is released, the arm 23 exerts yielding pressure to return the picker stick to its outward position.

As the picker stick approaches its extreme outward position, however, the effective action of the arm 23 is abruptly stopped by the strap 25, which prevents the arm from following the picker stick beyond a certain predetermined limit. In its continued outward movement, the stick is cushioned by the yielding stop 20, which exerts a yielding pressure in the opposite direction from that exerted by the arm 23. The picker stick is thus quickly and yieldingly restored to outward limit of movement.

Having thus described my invention and the advantages thereof, I do not wish to be limited to the details herein disclosed otherwise than as set forth in the claims, but what I claim is:—

1. In a loom, a picker stick, means to give said picker stick an inward operative movement, means to yieldingly return said picker stick toward outward position, and a check strap effective to render said restoring means

inoperative and to thereby limit such restoring action while permitting limited continuous free movement of said picker stick.

2. In a loom, a picker stick, means to give said picker stick an inward operative movement, means to yieldingly return said picker stick toward outward position, said latter means being operative throughout the major portion of the range of movement of said picker stick, means to render said restoring means inoperative as said picker stick closely approaches its outward position, said picker stick having an additional limited free outward movement after said restoring means becomes inoperative, and an additional device effective to yieldingly resist final outward movement of said picker stick.

3. In a loom, a rock shaft, an end bracket

therefor, a picker stick pivoted on said bracket, an arm pivoted on said bracket adjacent said picker stick, a spring to yieldingly force said arm against said stick, and means to limit such yielding movement of said arm.

4. In a loom, a rock shaft, an end bracket therefor, a picker stick pivoted on said bracket, an arm pivoted on said bracket adjacent said picker stick, a spring to yieldingly force said arm against said stick, and a flexible member fixed at one end to the outer end of said arm and at the other end to a fixed part of the loom and limiting outward restoring movement of said arm.

In testimony whereof I have hereunto affixed my signature.

ANDREW ARCHER.
